Patented Dec. 27, 1921.

UNITED STATES PATENT OFFICE.

WILLIAM F. KONIG, OF SAN FRANCISCO, CALIFORNIA, ASSIGNOR OF ONE-HALF TO
JOHN C. McCANN, OF SAN FRANCISCO, CALIFORNIA.

RAT-GUARD.

1,401,540.

Specification of Letters Patent. Patented Dec. 27, 1921.

Application filed December 15, 1920. Serial No. 430,847.

To all whom it may concern:

Be it known that I, WILLIAM F. KONIG, a citizen of the United States, and resident of San Francisco, in the county of San Francisco and State of California, have invented a new and Improved Rat-Guard, of which the following is a full, clear, and exact description.

In connection with vessels, it is a well appreciated fact that most ports have an act 10 of legislation requiring that guards be placed upon the hawsers of vessels when the same is tied to the dock, to prevent rats from coming aboard, or landing from, the vessel 15 by means of the hawsers.

This precaution is taken with a view of preventing a spread of disease, the germs of which, as is well known, are often carried by these rodents.

With this in view, rat guards for the hawsers of ships have been devised, which 20 rat guards usually include a disk of material, provided with an opening through which the hawser was to be threaded. This 25 provision, prevented to a great extent the use of the hawser by rodents in landing and going to the ship.

However, certain objections have been noted in connection with devices of this type, 30 in that primarily the rat guard was usually inapplicable to more than one size of hawser, by virtue of the fact that the center opening of the same was of a specified diameter.

Further, it was necessary, in most cases, to thread the hawser through the opening which rendered the hawser difficult to handle, especially during the bustle of docking.

Also the guard often would not remain 40 transversely positioned upon the hawser, due to the shrinkage of the latter, etc. In this case it was often possible for the rats to climb over the guard.

Having these defects in mind, I have now 45 constructed a rat guard, which has, as its primary object the prevention of any possibility of a rodent utilizing the hawser when my guard is in applied position.

A further object of my invention is the 50 construction of a device of this nature which shall be adjustable so as to be applicable to various sizes of hawsers within the limits of its adjustability.

A still further object of my invention is 55 the provision of a guard which may be ap-

plied to the hawser subsequent to the positioning of the latter between the vessel and dock.

Various further objects of my invention will appear in the annexed specification and 60 drawings, which latter present one practical embodiment of my invention, and in which—

Figure 1 is a perspective view of my improved guard in applied position upon the 65 hawser.

Fig. 2 is an end view thereof.

Fig. 3 is a fragmentary view showing certain of the parts of the guard.

Fig. 4 is an enlarged sectional side view 70 taken along the lines 4—4 of Fig. 2.

Fig. 5 is a perspective view of one of the elements of the guard, and

Fig. 6 is a side view of one of the units 75 of the guard.

In these views the reference numeral 10 indicates the hawser upon which the guard is positioned, in a plane at all times substantially transverse to the same, so that any possibility of a rodent climbing over the 80 guard is effectually prevented.

Referring now more particularly to Fig. 5 it will be seen that one of the main elements of the guard conveniently includes a disk 11, which may be semi-circular, and 85 which is conveniently provided with a cut-out portion 12, intermediate the ends of its straight edge, the face of such cutout portion being preferably curved to conform roughly to the contour of a hawser. 90

The side edges of the semi-circular portion of the disk are provided adjacent the straight edge, with inwardly extending flange portions 13, whereby to provide 95 grooves at this point.

These grooves, as will be noted, present a straight face, and as will be seen, reference being had to Figs. 1, 2 and 4, are adapted to receive a second substantially circular disk 14. The two disks when assembled 100 together, in this manner present a substantially circular body.

As will be noted, the second disk 14, is also provided with a recess 12, and both of these disks have secured to them transversely curved sleeve portions 15, having their ends extending beyond the side face of the disk, and adapted to lie substantially parallel to the body of the hawser 10, such sleeve portions resting within the recesses 110

12, and adjacent the grooved face of the same.

Thus I have provided a guard which shall be bodily extensible, so that the central opening of the same may be distended to accommodate various sizes of hawsers, the sleeves 15 serving at all times to retain the body of the guard transversely to the hawser with which they contact.

10 To now provide suitable means serving to retain the parts in applied position upon a hawser, and to effectually prevent a rodent from forcing these parts, in such a manner that it may crawl between the same, a 15 clamping strip 16 is conveniently affixed to each of the disks, and adjacent the sleeve 15 thereof. The central portion of this clamping strip serves to retain the end of a strip of material 17 in applied position, 20 which strip of material is preferably of canvas, and may be provided with laces 18, permitting of its being applied to the hawser 10 in such a manner, that the same is enveloped, as has been clearly indicated in 25 Figs. 1 and 4.

The ends of the clamping strip 16 are preferably extended, and spaced from the face of the disk with which they are associated, so as to overlap the face of the second 30 disk. By mounting the clamping strips 16 upon opposite faces of the disk it will be understood that this will provide a guarding element serving to effectually retain the parts in proper relationship, one with 35 the other.

Thus I have provided a guard which is applicable to various sizes of hawsers, and may be applied to the same, subsequent to their being extended between the dock and 40 the vessel, and in which no possibility of a rodent passing through or over the guard exists.

Obviously numerous modifications of structure might readily be resorted to with-

out in the least departing from the spirit 45 of my invention, which I claim as:

1. A rat guard, including a pair of units, one of said units presenting grooves adapted to receive certain parts of the side edges of the second of the same, each of said units 50 being formed with a recessed portion, these recessed portions being adapted to aline with each other to provide a common opening through both of the units, and clamping strips secured to one of the faces of each 55 of said units, and strips of material, having one of their ends interposed between said clamping strips and face of said units.

2. A rat guard, including a pair of units, one of said units presenting grooves adapted 60 to receive certain parts of the side edges of the second of the same, each of said units being formed with a recessed portion, these recessed portions being adapted to aline with each other to provide a common 65 opening through both of the units, clamping strips secured to one of the faces of each of said units, and strips of material having one of their ends interposed between said clamping strips and face of said units, 70 and means attached to said strips of material for permitting the same to envelop the hawser.

3. A rat guard, including a pair of units, one of said units presenting grooves adapted 75 to receive certain parts of the side edges of the second of the same, each of said units being formed with a recessed portion, these recessed portions being adapted to aline with each other to provide a common opening through both of the units, clamping strips secured to one of the faces of each 80 of said units, the clamping strips of each of said units having their ends extended so as to overlap the face adjacent the side edges 85 of the recessed portion of the second unit.

WILLIAM F. KONIG.
